UNITED STATES PATENT OFFICE.

GEORGE RUSTON, OF FREEPORT, ILLINOIS.

IMPROVEMENT IN WAGON-SEAT FASTENERS.

Specification forming part of Letters Patent No. **141,292**, dated July 29, 1873; application filed May 10, 1873.

To all whom it may concern:

Be it known that I, GEORGE RUSTON, of Freeport, in the county of Stephenson and State of Illinois, have invented a new and Improved Wagon-Seat Fastener, of which the following is a specification:

In the accompanying drawing, Figure 1 is a front view of my improved fastener, as applied to the side of the seat and locked to the body of the wagon; and Fig. 2 is a vertical transverse section of the same on the line *c c*, Fig. 2, dotted lines indicating its position when separating the seat from the wagon.

Similar letters of reference indicate corresponding parts.

The object of my invention is to provide a fastener or latch, which is applied to both sides of a wagon-seat, to connect the same firmly to the body of the wagon, so that the displacing or detaching of the seat is prevented, and a secure seat obtained. My invention consists of a hinge-fastener combined with a latch applied to the sides of the wagon-seat, the hinge-fastener with bent end closing over the guide-strip of the wagon-body in connection with a pin locking into a hole of the same.

In the drawing, A represents the side of the body of the wagon; B, the guide-strip running near the upper edge of the same; and C, the side support of the seat, grooved to fit over the side A. The latch D is applied with

screws, or otherwise, to the inside of the side support C, having hinged at the lower edge the fastener E, of sufficient length to lock over guide-strip B. Its lower end *a* is, for this purpose, bent toward the wagon side A, and closes over the lower side of the strip B. A pin or lug, *b*, applied at the lower side of seat-support C, locks into a hole or recess, *b'*, of guide-strip, at the place where the seat is required. By sliding the seat along guide-strip B till the lugs *b* engage in holes *b'*, and bringing hinge-fasteners C down over strips B, and locking them firmly by bolts *d* of latches D, a rigid attaching of the wagon-seat is obtained.

By providing different holes at equal intervals, the seat may be adjusted to any desired position on the wagon. To disconnect the seat, the bolts are withdrawn, and the hinges and lugs separated from the guide-strips.

Having thus described my invention, I claim as new and desire to secure by Letters Patent—

The combination, with the side A, the side support grooved to fit over it, and the guide-strip B, of the latch D, hinge-fastener E, and bolt *d*, as and for the purpose described.

GEORGE RUSTON.
